MECHANISM FOR ADJUSTING MACHINE TOOLS

Application filed May 12, 1927, Serial No. 190,700, and in Germany May 14, 1926.

My invention relates to mechanism for adjusting the tools of machine tools, the rolls of rolling mills and the like.

Such adjustments are frequently accomplished by electric motors which are brought to rest after a certain number of revolutions which correspond with the desired adjustment of the adjustable tool or roll. The control of such motors presents certain difficulties to the attendant and assumes a certain skill on his part, because he is obliged while carrying out the adjustment to watch constantly the instrument which indicates the revolutions of the motor, so that a certain inaccuracy in the adjustment is liable to occur and furthermore in some of the mechanisms employed more than one attendant is required for carrying out the adjustment.

My invention consists of a mechanism which permits the adjustment of the tools or rolls to be carried out in such a way that the attendant makes the desired settings prior to the adjusting operation itself on a counting mechanism, so that afterwards he has only to start the adjusting or screw-down motor. The stopping of the motor takes place automatically. The automatic stopping of the adjusting motor after it has performed a definite number of revolutions takes place by the motor driving a counting mechanism stepped in decades, the individual decade counting units being designed as freely adjustable contacts. The motor is brought to rest when all the counting units contacts connected in series make contact simultaneously.

An embodiment of my invention as applied to the screw-down device of a rolling mill is diagrammatically illustrated in the drawing affixed hereto. In rolling mills it is essential that the accurate spacing of the rolls should be capable of being carried out in as simple a manner as possible.

Referring to the drawing it will be seen that the lower roll 11 of the rolling mill, the drive of which is not shown, is journaled in stationary bearings in suitable standards. The roll 12 is adjustable in such a way that when the screw-threaded spindles 13 are turned the roll is lowered or raised according to the direction of rotation.

The adjustment of the roll 12 is effected by means of the screw-down motor 14 which drives the spindles 13 through a worm and worm-wheel 15. A definite number of revolutions of the motor 14 corresponds with a definite spacing of the rolls 11 and 12. As screw-down motor a three-phase motor is shown in the drawing by way of example, but it will be understood that any other kind of motor might be employed. The stator of the motor is connected with the three-phase system R S T by the lines 16. The stator circuit of the motor is completed by closing the switch 21, the contactor coil 22 then closing the contacts 25, 26 in the stator circuit. In the circuit of the switch 21 and the coil 22 are connected the contacts 23 which are closed when the contactor coil 24 is not excited. Instead of the switch 21 a push button with automatic holding circuit might be employed.

For adjusting a definite number of revolutions of the screw-down motor or a definite spacing between the rolls an adjusting mechanism is according to my invention provided which is designed in the manner of the well-known decade counting mechanisms.

The single-tooth wheel 31 gears with the spur wheel 32 with ten notches or gaps so that for each complete revolution of the wheel 31 the wheel 32 is turned by 1/10th of its circumference. The wheel 32 is also designed as ordinary spur wheel and meshes with the spur wheel 33 having an equal number of teeth. The wheel 33 is also constructed as single-tooth wheel and engages the spur wheel 34 which is provided with 10 notches or gaps. The wheel 34 drives the wheel 35 having an equal number of teeth. With the toothed wheels 31, 33 and 35 are combined contact-bearing drums 51, 53 and 55 each fitted with a slip-ring contact 52, 54, 56 which covers about 1/10th of the circumference of the drum. Upon the shafts of the three wheels 31, 33 and 35 are mounted adjusting levers or fingers 41, 43 and 45 with contact brushes 42, 44, 46. Each of these levers is adapted to be adjusted in the positions 0 to 9 by means of notches. The shaft 27 of the toothed wheel 31 or the contact drum 51 is 100

driven by the screw-down motor 15 by way of the gear wheels 28, for instance with the ratio 1:10 so that the contact drum 51 performs only one tenth, the contact drum 53 one hundredth and the contact drum 55 one thousandth the number of revolutions of the screw-down motor 14.

The mechanism operates in the following manner: Assuming that the spacing between 10 the rolls 11 and 12 should be 642 mm., this corresponds with 6420 revolutions of the screw-down motor 14. The adjusting lever or finger 45 is then placed into the position 6, the adjusting lever 43 into the position 4, and 15 the adjusting lever 41 into the position 2. The switch 21 is now closed. The contactor coil 22 attracts its core so that the contacts 25 and 26 in the stator circuit of the screw-down motor are closed. The motor 14 starts 20 and rotates the contact-bearing drums 51, 53, 55. During each complete revolution of the drum 51 the brush 42 of the finger 41 makes one contact with the slip-ring contact 52. This closing of the contact remains, however, 25 inoperative for the time being. The position is similar in regard to the contact-bearing drum 53, the slip-ring contact 54 of which makes contact with the brush 44 of the finger 43 once during each complete revolution. 30 As soon, however, as the slip-ring contact 56 makes contact with the brush 46 of the finger 45, a circuit is completed from S across the coil 24, brush 42, contact 52, slip-ring 61, brush 44, contact 54, slip-ring 63, brush 46, 35 contact 56, slip-ring 65 to T. The coil 24 attracts its core and opens the circuit of the contactor coil 22, so that the contacts 25, 26 in the stator circuit of the screw-down motor are opened and the motor comes to rest. The 40 adjustment of the rolls 11 and 12 is then finished. The attendant has thus only to adjust the levers or fingers 41, 43 and 45 and need not trouble about the adjustment of the rolls any more. The screw-down motor 45 comes to rest at the proper time when the desired spacing of the rolls has been attained.

The control of the adjusting or screw-down motor may according to my invention be still further improved by reducing its speed step-wise after it has performed a certain number of revolutions. This may, for instance, be attained in the following manner. When the motor has made 6000 revolutions out of an adjusted 6420 revolutions, a contactor coil 71 50 is excited by the contact drums and contact brushes on the counting mechanism and inserts by means of the contacts 73 resistor sections 75 into the rotor circuit of the motor which were previously short-circuited. By 55 the insertion of this resistor the speed of the screw-down motor is reduced by a certain step. As soon as the motor has performed another 400 revolutions the resistor sections 76 are switched into the rotor circuit by means of the contactor coil 72 and the con-

tacts 74 so that the speed of the motor drops by another step. When the motor has then performed a further 20 revolutions the circuit of the contactor 24 is completed across the brushes 42, 44, 46 and the slip-ring contacts 52, 54, 56, the stator circuit of the motor 14 being opened, as described above.

My improved mechanism brings about a great simplification of the process of rolling and greatly relieves the attendant or reduces the number of skilled attendants otherwise required.

Various modifications and changes may be made without departing from the spirit and the scope of the invention, and I desire, therefore, that only such limitations shall be placed thereon as are imposed by the prior art.

I claim as my invention:—

1. In combination, a member disposed to be set in different positions, an adjusting mechanism, a motor for actuating said mechanism, means for starting the motor, means for varying the speed of the motor, and means actuated by the motor for stopping it in a predetermined position, said means comprising a train of rotatable members disposed to operate at different speeds, and a corresponding number of adjustable members disposed to be set in predetermined angular positions, co-operating contact members carried by the rotatable and adjustable members, said contact members being disposed to individually effect the operation of the speed varying means and to affect the motor stopping means only when said contact members are actuated into engagement simultaneously.

2. In combination with an adjustable member, an adjusting mechanism, a motor for actuating the adjusting mechanism, a control circuit for the motor, a plurality of rotatable switches connected in series-circuit relation to control said circuit, transmission means interposed between the motor and one of the rotatable switches, and gear mechanism interposed between the switches for connecting said switches in tandem relation, said gear mechanism being disposed to cause the movement of the switches at different speeds thereby to provide a definite relative position of the series of switches responsive to a predetermined movement of the adjustable member and means responsive to the closure of the individual rotatable switches for controlling the speed of the motor.

3. The combination with an adjustable member of an adjusting mechanism, a motor for actuating the adjusting mechanism, an electro-magnetic line switch for starting and stopping the motor, a relay disposed to control the energization of the line switch, a circuit for operating the relay, and means actuated by the motor for effecting the operation of the relay in response to a predetermined movement of the adjustable member,

said means comprising a series of rotatable counting discs geared for operation at different speeds, contact segments carried by the discs, and adjustable contact members disposed in co-operative relation to the movable segments, said contact segments and members being connected in series relation to the relay operating circuit to thereby effect the operation of the relay to stop the motor in response to the simultaneous engagement of all the contact members and segments and means responsive to the individual engagement of the contact members and segments for reducing the motor speed before a stopping operation is effected.

4. The combination with an adjustable member, of an adjusting mechanism, a motor for actuating said mechanism, a source of power for the motor, a main switch for connecting the motor to the power source, a starting resistor for the motor, switches disposed to short-circuit the resistor in sections, and a counting mechanism actuated by the motor for controlling the operation of all the switches, said counting mechanism comprising a plurality of rotatable switch elements geared in tandem relation to rotate at different speeds, a circuit for controlling the main switch including all the rotatable switch elements in series relation, and a control circuit for each resistor short circuiting switch including one of said rotatable switch elements, thereby to effect a reduction in the motor speed in response to the closure of one switch element, and the stopping of the motor in response to the simultaneous closure of all the switch elements.

In testimony whereof, I have hereunto subscribed my name at Frankfort-on-the-Main,
40 Germany, April 23, 1927.
